UNITED STATES PATENT OFFICE.

LEOPOLD M. LUX, OF MINNEAPOLIS, MINNESOTA.

ARTIFICIAL LEG.

1,213,823.

Specification of Letters Patent. Patented Jan. 30, 1917.

Application filed September 24, 1915. Serial No. 52,484.

To all whom it may concern:

Be it known that I, LEOPOLD M. LUX, a citizen of the United States, residing at Minneapolis, in the county of Hennepin and State of Minnesota, have invented certain new and useful Improvements in Artificial Legs; and I do hereby declare the following to be a full, clear, and exact description of the invention, such as will enable others skilled in the art to which it appertains to make and use the same.

My invention relates to artificial limbs, and has for its object to simplify and improve the construction thereof.

In accordance with my invention, I make the improved artificial limb of a desired form, without a seam or joint, from a vulcanized fiber tube. The original jointless fiber tube which is employed for this purpose is of a known commercial form made cylindrical, or without taper. This fiber tube is placed around a suitable form, usually a sectional form, which has the desired shape to be given to the limb, and which is capable of being taken out of the completed limb. The fiber tube is first soaked in water for several days, so that it is considerably softened. Then it is placed around a form, and by a succession of compressions is reduced to the shape of the form. Such compressions are best given by wrapping the rope tightly around a softened fiber tube, while it is placed around the form. This may be done by placing the form in a lathe, or other suitable machine, and rotating the same and the tube and wrapping the rope tightly around the tube while the rope is held, under tension or pulling strain. In this way, when the rope is closely and tightly wound around the softened fiber tube, it will be reduced to the shape of the said form. Usually, the wrapping and compressing operation will have to be repeated several times before the fiber tube will be reduced to the shape of the form, but this depends somewhat on the amount that the tube has to be reduced. In making an artificial leg, for example, the taper, in some instances, will be much more than in others.

The invention consists both in the product and in the process by which the same is produced.

In the accompanying drawings which illustrate the invention, like characters indicate like parts throughout the several views.

Referring to the drawings: Figure 1 is a view partly in plan and partly in horizontal section showing a fiber tube or tube section from which the artificial limb is to be formed; Fig. 2 shows a sectional form; Fig. 3 shows the fiber tube placed around the form and compressed and reduced to the shape of the form; and Fig. 4 shows the complete limb, which, as here illustrated, is the lower leg section.

The numeral 1 indicates the fiber tube, and the numeral 2 the sectional form over which the limb is shaped. After the limb is completed, the form 2 may be taken apart and removed therefrom.

The numeral 3 indicates a rope tightly wrapped around the fiber tube. The completed seamless limb or leg is, in the drawings, marked 1^a.

A leg or limb made as above described, will have a maximum strength with a minimum of weight and will not only be much neater in appearance than a limb formed with seams, but will have a perfectly smooth exterior which is, as is obvious, highly desirable in an artificial leg or limb. This improved leg has a varying cross section or taper and the particles thereof are variously displaced in the varying cross sections, by the above described process of making the same. The displacement of particles under high compression produced as above described, also gives to the completed product, when the latter is dried, greater toughness and strength and a considerable resilience, all of which features are highly desirable in an artificial leg or limb.

For making the improved artificial limb, as above described, I have, in practice, used a vulcanized vegetable fiber tube or cylinder of known commercial form, which, when dry, or in normal condition, is very hard, tough and strong. Vulcanized vegetable fiber is an ideal material for making the body portions of artificial limbs, but hitherto, it has been considered necessary to make the same with seams in order to get the desired shape in the limb.

What I claim is:

1. As a new article of manufacture, a vegetable fiber artificial limb having a seamless tubular form of varying cross section and with the particles thereof variously displaced in the varying cross sections thereof. 110
2. The process of making an artificial limb from a seamless vegetable fiber tube

which consists in placing the fiber tube around a form having a varying cross section, and in reducing the said tube to the shape of said form, by external compression.

5 3. The process of making an artificial limb from a seamless vegetable fiber tube which consists, first in soaking the original tube in water to soften the same, second, in placing the said softened tube around a

form having a varying cross section, and 10 third, in reducing the said tube to the shape of the said form, by external compression.

In testimony whereof I affix my signature in presence of two witnesses.

LEOPOLD M. LUX.
